Atty.

UNITED STATES PATENT OFFICE

ALFRED SOULIER, OF CACHAN, FRANCE

VOLTAGE AND CURRENT REGULATOR FOR ALTERNATING-CURRENT CIRCUITS

Application filed September 27, 1928, Serial No. 308,777, and in Belgium October 4, 1927.

The present invention relates to voltage and current regulators for alternating current circuits.

One of the objects of the invention is to provide a device capable of transforming a variable alternating current potential into a potential which is substantially constant. 5

A further object is to provide means for regulating a source of current of variable 10 amperage.

Still further objects will appear in the course of the detailed description now to be given with reference to the accompanying drawings in which:—

15 Fig. 1 is a diagram of one constructive embodiment of the invention;

Fig. 2 is a vector diagram showing the manner in which the circuit shown in Fig. 1 operates.

20 Referring to the various figures of the drawing, f^1 , f^2 are the terminals of an alternating current circuit in which the voltage values vary between certain limits,—a vertical solenoid provided with terminals e^1 , e^2 ,— b , a vertical iron core mounted on a resilient system b^1 adapted to compensate at least part of the weight of core b and to act as a sort of elastic support for the latter, and coupled with means for instance a dash-pot b^2 adapted to 25 prevent periodical vibrations of core b ,— e a condenser connected across a pair of terminals d^1 , d^2 leading to the terminals of constant potential.

30 The characteristics of the solenoid and its core and of condenser c are so chosen that the variation of potential across f^1 , f^2 cause core b to move up and down inside the solenoid and vary the self-induction of the system so that the potential across terminals 35 d^1 , d^2 of condenser e remains substantially constant.

40 In the vector diagram shown in Fig. 2, the amperage I is taken as origin. Since the solenoid and the condenser are mounted in series they will be traversed by the same current I . If the resistance of the solenoid and of the condenser are neglected, the potentials U_s and U_c respectively of the latter elements 45 will be displaced in advance and behind the

vector current by 90° . The vector tension U_s and U_c are, therefore, in opposition.

The relation between the potential being supplied U_m and potentials U_s and U_c is the following:

$$U_m = U_s - U_c$$

Let it be supposed, now, that the potential of the main or supply circuit U_m varies. Since condenser c has a fixed value and solenoid b has a movable core, there will be a variation of the difference of potential across the terminals of the solenoid due to the in-and-out movement of the core tending to equilibrate the potential of the main circuit. 65

The potential across the terminals of the condenser will remain substantially constant, since any variation in the potential of the main circuit will be balanced by a corresponding variation in the counter electromotive force of self-induction. That is to say:

$$U_s - U_m = U_c = \text{constant.}$$

It is to be noted that the functioning of the system is influenced by the nature of the condenser. Thus it is found that the best results are obtained with electrolytic condensers and this appears to be due to the fact 80 that, when an electrolytic condenser is working near the limiting voltage, any increase in potential tends to produce electrolysis. The active current which results permits the desired regulation to be obtained. 85

The regulating device may be combined with radio amplifiers to give more powerful effects than those obtainable with transformers. It may also be applied to heating circuits for electron or X-ray tubes or to any 90 thermionic device wherein a constant heating current is desired. Applied to photometers, it permits a constant voltage to be maintained across the terminals of the lamps being compared despite considerable variations in the main current supply circuit (40-50%). 95

What I claim is:—

In combination with a circuit carrying an alternating-current of varying poten- 100

tial, a solenoid mounted in series with said circuit, means operable by variations of the current traversing said solenoid to vary the self-inductance thereof, and an electrolytic 5 condenser inserted in parallel between part of said circuit and one terminal of said solenoid.

In testimony whereof I have hereunto set my hand.

ALFRED SOULIER.
